UNITED STATES PATENT OFFICE.

OSWALD SEELIGER, OF LOCKHART, TEXAS.

HORSESHOE-NAIL CLINCHER.

SPECIFICATION forming part of Letters Patent No. 512,228, dated January 2, 1894.

Application filed February 27, 1893. Serial No. 463,842. (No model.)

To all whom it may concern:

Be it known that I, OSWALD SEELIGER, a citizen of the United States, and a resident of Lockhart, in the county of Caldwell and State 5 of Texas, have invented certain new and useful Improvements in Devices for Clinching Horseshoe-Nails; and I do hereby declare that the following is a full, clear, and exact description of the invention, which will enable 10 others skilled in the art to which it appertains to make and use the same, reference being had to the accompanying drawing, which forms a part of this specification.

My invention relates to improvements in 15 clinchers for clinching horseshoe nails, the object being to provide a novel construction of the same by which I obtain superior advantages with respect to simplicity and efficiency in operation.

20 The invention consists in the novel construction and combination of parts herein-after fully described and claimed.

In the accompanying drawing: the figure 25 represents a perspective view of a clincher constructed in accordance with my invention.

In the said drawing the reference numeral 1 designates a limb having a jaw 2, formed or provided with serrations or teeth 3. Secured to limb 1 are two upwardly extending 30 plates 12, to which is pivoted a curved jaw 5, having teeth or serrations 6, and formed with a short beveled extension 7. Also secured to said limb are two upwardly projecting plates 13, at a point intermediate of its jaw and the 35 opposite end, to which plates is pivoted a lever 8, the short arm 9, of which is beveled and engages with the beveled extension of the jaw 5. Located between the limb 1 and jaw 5, and secured to the former is the inner end of 40 a spring 10, consisting of a flat piece of spring metal having its outer end bent or curved upwardly and bearing against the jaw 5, for the purpose of returning said jaw to normal po-

sition after having been actuated by the lever 8.

The operation will be readily understood. In practice after the shoe has been fitted to a horse's hoof and the nail driven in, in the ordinary manner, the jaw 2 of the limb is placed upon the head of the nail, the teeth therein preventing it from slipping, while the curved jaw is brought up and engaged with the point of the nail. By now pressing upon the lever 8, its beveled end will engage with the beveled extension of the jaw 2, causing the latter 55 to be actuated and the point of the nail flattened down.

From the above it will be seen that a very simple and efficient device is produced by which a horseshoe nail may be clinched and 60 flattened in a very rapid and efficient manner, and by its peculiar construction, but comparatively little power is required to manipulate the same.

Having thus described my invention, what 65 I claim is—

A horse-shoe nail-clincher, combining in its structure, the limb with a serrated jaw and a handle, the curved jaw provided with teeth or serrations on its convex side and having a 70 beveled extension, the upwardly extending plates secured to said limb, the lever pivoted to the intermediate upwardly projecting plates secured to said limb, having its short arm beveled and engaging with said extension, and the spring consisting of a flat metal plate secured to said limb and having its outer end bent upwardly so as to engage with the curved jaw, substantially as described.

In testimony that I claim the foregoing as 80 my own I have hereunto affixed my signature in presence of two witnesses.

OSWALD SEELIGER.
